US0D1017595S

(12) **United States Design Patent** (10) **Patent No.:** **US D1,017,595 S**
(45) **Date of Patent:** **** Mar. 12, 2024**

(54) **NOTEBOOK COMPUTER**

(71) Applicant: **Samsung Electronics Co., Ltd.**,
Suwon-si (KR)

(72) Inventor: **Jinsun Lee**, Suwon-si (KR)

(73) Assignee: **SAMSUNG ELECTRONICS CO., LTD.**, Suwon-si (KR)

(**) Term: **15 Years**

(21) Appl. No.: **29/820,995**

(22) Filed: **Dec. 27, 2021**

(30) **Foreign Application Priority Data**

Oct. 25, 2021 (KR) 30-2021-0050348

CLAIM

The ornamental design for a notebook computer, as shown
and described.

DESCRIPTION

FIG. 1 is a top perspective view of a notebook computer
showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

(Continued)

The evenly-dashed broken lines in the drawings illustrate portions of the notebook computer that form no part of the claimed design.
